UNITED STATES PATENT OFFICE.

DAVID KAUFMAN AND MORRIS MINTZ, OF BRONX, NEW YORK.

WATERPROOF CONTAINER.

Application filed November 26, 1927. Serial No. 235,992.

This invention relates to waterproof containers and more particularly to a novel and improved receptacle capable of being attached to a bathing belt for instance and designed to retain cigarettes and matches as well as other small articles free of moisture.

One of the objects of our invention is to provide a waterproof container preferably of metal and having a removable receptacle associated with a cover or closure at one end and with a separate cover or closure at the opposite end, the interior being lined preferably with rubber to prevent the penetration of moisture to the article being carried.

15 To enable others skilled in the art to more fully comprehend the underlying features of our invention, reference is had to the accompanying drawing wherein

Fig. 1 is a perspective view, partly broken away showing our invention when connected to a bathing belt.

Fig. 2 is a vertical sectional view.

Fig. 3 is a section taken on the line 3—3 of Fig. 2.

25 Fig. 4 is a perspective view of the interior container associated with a cover or closure.

Fig. 5 is a sectional view of a slightly modified form of the invention.

Referring now to the drawings, 5 designates an outer cylindrical container preferably of light metal, threaded at its open end as at 6 and at its opposite end as at 7. The interior of the container is lined with waterproof material, such as rubber, indicated by numeral 8, and extending throughout the major portion thereof. The insulating material forms a bottom or common partition 9 between a large compartment or chamber and a smaller compartment or chamber at one end thereof. Within the large compartment or chamber there is provided a removable receptacle, preferably of metal, the body portion 10 of which is cylindrical in shape and of a size to frictionally fit within said compartment. The removable receptacle is provided with a closed bottom 11 and the top is fastened in any suitable manner to a cover or closure 12 which is threaded to the end of the outer cylindrical container 5.

55 The removable receptacle is equipped with a segmental, longitudinal, curved shaped door 13, hinged at its bottom as at 14 so that when closed, the receptacle may frictionally fit within the outer cylindrical container, as shown by Fig. 2 of the drawing. The

door 13 is provided with a finger notch 10^a or indentation whereby the said door may be conveniently opened to the position shown by Fig. 4. Being connected with the closure 12, the inner cylindrical container rotates therewith when said closure is being fastened to the threaded end of the outer container.

In the opposite end of the outer container, there is provided a cylindrical liner 13^a for the smaller compartment which is closed by a threaded closure 14^a, threaded to the opposite end of the said outer container. The last mentioned compartment thus provides an additional and separable compartment in which small coins or other personal articles may be retained.

The interior removable receptacle is particularly designed to receive cigarettes and matches to protect the same from moisture when the device is attached to and worn on a bathing belt for instance. In this connection, we provide a short threaded element 15 adapted to pass through an opening in a belt buckle 16 for instance and fastened thereto by a nut 17. The container may be thus fastened either in a horizontal or vertical position as desired.

25 In Fig. 5 there is shown a slightly modified form of the invention in which the inner, removable receptacle is dispensed with, the insulating material forming the top and bottom separable compartments for receiving the personal articles of the character above referred to. In this form of the invention there is provided a top and a bottom closure for the respective compartments.

While we have shown and described our invention with some degree of particularity, we realize that in practice various alterations therein may be made. We therefore reserve the right and privilege of changing the form of the details of construction or otherwise altering the arrangement of the correlated parts without departing from the spirit of the invention or the scope of the subject matter being claimed.

Having shown and described our invention, what we claim as new and desire to secure by Letters Patent is:—

1. A device of the class described comprising a container threaded at each end, a waterproof lining for said container, a removable receptacle within said container, said receptacle having a top closure cooperating with the thread at one end of said

container and a threaded closure at the opposite end of said container.

2. A device of the class described comprising a container threaded at each end, a waterproof lining for said container, said lining forming a partition and dividing the container into two compartments, a removable receptacle within one compartment, said receptacle having a top closure cooperating with the thread at one end of said container and a threaded closure at the opposite end of said container.

3. A device of the class described comprising a container threaded at each end, a waterproof lining for said container, said lining forming a partition and dividing the interior into a major and smaller compartment, a removable receptacle within the major compartment, a hinged door for said receptacle, a threaded closure at one end of said receptacle adapted to be threaded to one end of the container, and a threaded closure for the opposite end of the container.

4. A device of the class described comprising a cylindrical container threaded at each end, a waterproof lining for said container, said lining forming a partition and

dividing the interior into a major and a smaller compartment, a removable receptacle interfitting within the major compartment, 30 a side door hinged at its bottom connected to said removable receptacle, a threaded closure at one end of said receptacle adapted to be threaded to one end of said container, and a threaded closure for the opposite end 35 of said container.

5. A device of the class described comprising a cylindrical container threaded at each end, a waterproof lining for said container, said lining forming a partition and dividing 40 the interior into a major and a smaller compartment, a removable receptacle interfitting within the major compartment, a side door hinged at its bottom connected to said removable receptacle, a threaded closure at 45 one end of said receptacle adapted to be threaded to one end of said container, and a threaded closure for the opposite end of said container, and means for attaching said body to a belt buckle. 50

In testimony whereof we affix our signatures.

DAVID KAUFMAN.
MORRIS MINTZ.
